(**) Term: **14 Years**

CLAIM

(21) Appl. No.: **29/134,970**

The ornamental design for a tampon insertion training aid, as shown and described.

(22) Filed: **Jan. 3, 2001**

DESCRIPTION

(51) LOC (7) Cl. **19-07**

FIG. 1 is a top plan view of a tampon insertion training aid embodying our design.

(52) U.S. Cl. **D19/62**

FIG. 2 is a back plan view thereof.

(58) Field of Search D19/62; 434/272, 434/273, 262, 267

FIG. 3 is a front plan view thereof.

(56) **References Cited**

FIG. 4 is a bottom plan view thereof.

U.S. PATENT DOCUMENTS

FIG. 5. is a right side view thereof, the left side view being a mirror image in appearance; and,

2,132,226 * 10/1938 Wahlberg 434/273
2,495,568 * 1/1950 Coel 434/273
3,766,666 * 10/1973 Stroop 434/273

FIG. 6 is a perspective view thereof.
